(57) **CLAIM**

The ornamental design for a re-sealable can lid, as shown and described.

DESCRIPTION

FIG. 1 is a top perspective view of a re-sealable can lid according to a first embodiment of my new design;

FIG. 2 is a reverse perspective view thereof;

FIG. 3 is a top view thereof;

FIG. 4 is a bottom view thereof;

FIG. 5 is a front perspective view thereof;

FIG. 6 is a rear view thereof;

FIG. 7 is a left side view thereof;

FIG. 8 is a top view of a re-sealable can lid according to a second embodiment of my new design;

FIG. 9 is a bottom view thereof;

FIG. 10 is a front view thereof; with the rear view, left side view and right side view being identical;

FIG. 11 is an exploded view thereof;

FIG. 12 is another exploded view thereof;

FIG. 13 is a top view of a re-sealable can lid according to a third embodiment of my new design;

FIG. 14 is another top view with the lid partially open;

FIG. 15 is a perspective view thereof;

FIG. 16 is another perspective view with the lid partially open;

FIG. 17 is a rear perspective view thereof; and,

FIG. 18 is another rear perspective view with the lid partially open.

One or more views (e.g., bottom or mirror/identical opposite view) may not be shown as those views are unornamented or simply not claimed in a given embodiment.

The broken lines represent environmental structure or unclaimed portions of the re-sealable can lid and do not form a portion of the claimed design.
